[57] CLAIM

I claim the ornamental design for a telephone handset, as shown.

DESCRIPTION

FIG. 1 is a bottom perspective view of a telephone handset, showing my new design.

FIG. 2 is a top perspective view thereof.

FIG. 3 is a right side perspective view thereof.

FIG. 4 is a left side perspective view thereof.

FIG. 5 is an enlarged front perspective view thereof; and,
FIG. 6 is an enlarged rear perspective view thereof.
